UNITED STATES PATENT OFFICE

HENRY DREYFUS, OF LONDON, AND FRANK CORBYN HALE, OF SPONDON, NEAR DERBY, ENGLAND, ASSIGNORS TO CELANESE CORPORATION OF AMERICA, A CORPORATION OF DELAWARE

SHUTTLELESS LOOM

Application filed October 15, 1930, Serial No. 488,828, and in Great Britain October 23, 1929.

This invention relates to looms, and more particularly to shuttleless looms; i. e., those receiving weft from a stationary supply at one or both sides of the looms.

5 A shuttleless loom according to the invention comprises in combination means for measuring weft at a side of the loom in the form of a loop whose length is sufficient for two picks, weft-inserting means adapted to engage one limb of the loop and carry it part-way through the shed, and means for transferring the weft from the inserting means to weft-withdrawing means by which the weft is carried through the remainder of the shed, the weft which has thus been laid in the shed then being released by the withdrawing means.

If desired, a weft loop may be measured at one side of the loom only, the second limb 20 of the loop being laid in the shed in a manner similar to the first before a second loop is measured. For weft-mixing purposes, means may be arranged to measure two or more loops from which weft is inserted in any desired sequence.

The invention is, however, particularly 25 advantageous when operating to measure weft loops at both sides of the loom, since it allows two different weft yarns to be used and inserted in any desired order, for example, alternately by insertion from each side in turn, or two picks of one weft followed by two picks of the other. This facility in selection is useful in the weaving of crépe 30 fabrics in which the filling consists of both right and left hand twisted weft inserted either alternately or in pairs of one twist alternating with pairs of the other twist. It will be understood that the rate of picking 35 proceeds at the same rate whether consecutive weft lengths are drawn from the same side of the loom or from different sides, it merely being necessary in the latter case to arrange that the weft carrying devices on 40 each side of the loom serve both as inserting means and as withdrawing means, so that the actual picking operation is effected by the same movements of these devices, irrespective of the direction of the passage of 45 the weft through the shed. Alternatively,

two pairs of inserting and withdrawing devices may be employed, one pair effecting the passage of the weft in one direction through the shed, and the other pair in the other direction.

55 The weft inserting devices may take any convenient form and may be actuated in any suitable manner. For instance, they may consist of a pair of rods arranged to be propelled across the lay along the path normally followed by the shuttle of ordinary looms, the end of one rod being provided with a hook or the like adapted to engage a limb of the weft loop which has been measured at a side of the loom, and the end of the other rod having a hook or the like adapted to catch the weft held by the first rod and to draw the weft through the remainder of the shed after transfer.

60 Flexible metallic strips serving as weft inserting and withdrawing means as described in British Patent application No. 32195/29 filed 23rd October, 1929 and corresponding U. S. application S. No. 488,827 filed Oct. 15, 1930 may likewise be employed, such flexible 65 strips keeping the width of the loom to a minimum.

70 Tension means are preferably provided on the inserting and withdrawing devices so as to lay the weft evenly in the shed.

80 Any suitable type of loop forming and measuring means may be used which can form and present in turn to an inserting device two limbs of weft each of sufficient length 85 for a pick. In the accompanying drawings, which illustrate by way of example one form of loom according to the invention, the loop forming and measuring means shown are of the kind described in British Patent application No. 32194/29 filed 23rd October, 1929 and corresponding U. S. application S. No. 484,785 filed Sept. 27, 1930, these means being simple in character and readily adjustable in accordance with the width of fabric 90 to be woven.

95 In the drawings:—

100 Fig. 1 is a side elevation and Fig. 2 a front elevation of the loom provided with rods for inserting and withdrawing weft;

Figs. 3 and 4 are plan views of the ends of the inserting and withdrawing rods; and

Figs. 5, 6 and 7 are diagrams illustrating three stages during the measuring and insertion of the weft.

5 A weft supply package 10 is suitably positioned at the side of the loom for weft thread 11 to be led over a guide 12 to the weft loop measuring means.

10 These means comprise a rotatable disc 13 on which are mounted two pairs of trapping and severing devices 14, 15. The end of the weft thread is held in one trapping device 14 and rotation of the disc 13 causes the weft to pass between the jaws of the other trapping device 14, a hooked member associated with the severing device 15 guiding the thread in such a manner that it may slide freely through the severing device.

15 The weft now extends between the pairs of devices 14, and is there engaged by a pair of pegs 16 mounted on a chain 17 which runs along the side of the loom to draw out a loop of weft between the two devices 14. The pegs 16 are preferably formed as light rollers so as to reduce the tension imparted to the weft during the loop-forming operation. The chain 17 passes round sprockets 18 on brackets 19, 20 and is driven by a chain sprocket 30 at a speed which causes the peg 16 to traverse a distance approximately equal to the length of pick to be inserted, whilst the disc 13 rotates through half a revolution.

20 Driving of the chain and rotation of the disc 13 is derived from the crankshaft of the loom 21, spiral gears 22 on the crank-shaft driving a shaft 23, spiral gears 25 and a cross shaft 24. A pair of bevel wheels 26 mounted on the shaft 24 drive the disc 13 which is arranged to rotate about a vertical axis in a bracket 54. A further pair of bevel wheels 27 rotate spur gears 28 connected to the wheel 30 which drives the chain 17.

25 When the weft loop has been drawn to a sufficient length, the weft which has been running through one trapping device 14 is seized by that device, while the other device 14 releases the free end of the weft. Operation of the devices 14 is effected by bell-crank 30 levers connected to the moving jaws of the devices and engaging a cam 55. The severing devices 15 are similarly actuated by a cam 56. The cams 55, 56 are adjustably connected to the disc 13 so as to enable any alteration of timing to be readily carried out.

30 As the weft end is released from the one device 14, one limb of the weft loop is engaged and presented to the path of the weft inserter for insertion into the shed by a depressor 45 pivotally mounted on the lay 46 and connected by a rod 49 to a bell-crank lever 50 and cam bowl 52. A cam 51 mounted on the shaft 53 which rotates at half crank-shaft speed engages the cam bowl 52 to effect the presentation of a limb of the weft loop to the weft in-

35 sertor at alternate picks of the loom, i. e. at every pick to be inserted at the side of the loom where the depressor is arranged. A finger 32 has meanwhile been caused to enter the weft loop, so that the loop limb still 70 gripped by a trapping device 14 bends round the finger 32 in passing to the limb that has just been inserted into the shed. The finger 32 is operated from a cam 35 on a shaft 134 lying parallel to the shaft 24, the cam 35 being 75 connected to a gear 34 driven at the required speed from the shaft 24. The cam 35 is connected through a bell-crank lever 36 pivoted at 38 and a rod 39 pivoted to the lever 36 at 37 to a further bell-crank lever 40 pivoted at 41, which in turn raises a rod 42. This rod 42 is spring-coupled to two toggles 43, the ends of which are connected respectively to a spring-loaded slide rod 44 and to a rocker arm 33 carrying the finger 32. 85

40 While the toggles form a straight line, the finger 32 is unable to move against the tension of the weft passing round it, so that the tension of the weft is maintained during beat-up. The cam 35 then releases the toggles 43 90 and the finger 32 is free to move against the action of the spring on the rod 42 as the continued rotation of the disc 13 imparts greater tension on the remaining limb of the weft loop. This tension may be regulated 95 by adjusting the spring on the rod 42.

45 The cam 35 has a quick drop to allow the finger 32 to move suddenly out of position as a second pair of pegs 16 brings a second weft loop from the disc 13. The spring-loaded rod 44 allows the arm 33 to rock should the pegs catch the finger 32.

50 Motion of the lay 46 is obtained from a cam 29 mounted on the crankshaft of the loom, the contour of the cam being such that the lay is retained in its rearmost position for the major portion of the revolution of the shaft and is operated rapidly to effect beat-up, thus allowing sufficient time for operation of the weft inserters 65 to avoid danger of 110 the inserters fouling the warps.

55 The weft inserters 65 are arranged to carry the weft thread to a mid-shed position and to transfer the thread from one to the other, the weft being carried part way across the 115 shed by the one inserter and through the remainder of the shed by the second inserter. Operation of the inserters 65 is effected by links 64 coupled to the oscillating picking arms 63 which are operated by the cams 60 120 mounted on the shaft 62, which shaft 62 is supported in bearings 61, and is driven at crankshaft speed by gears connected to the crankshaft.

60 The weft-engaging heads 66 of the inserters 65 are shown to an increased scale in Figs. 3 and 4, each head comprising a fork 67 into which the weft enters when engaged by the inserter, and a hook 68 to which the weft is transferred when the heads meet in 130

the shed. A plate 70 guides the thread during transfer and guard plates 69 prevent possibility of the heads engaging the warps.

The heads thus enable each rod 65 to perform the dual function of inserting and withdrawing device, so that weft can be inserted from each side of the loom.

In order to adjust the amount of weft which has to be drawn with the loop to cover the distance between the edge of the fabric and the finger 32 after insertion of the first loop limb, which amount together with the second limb forms the second pick, the pegs 16 pass at each side of a fixed peg 71 so as to draw a subsidiary loop of weft at the bight end of the main loop. The peg 71 is adjustable in accordance with the width of fabric being woven, so that correct pick lengths can readily be formed for all widths of fabric. The disc 13 is also adjustable along the shaft 24 to enable the length of the main loop to be altered in accordance with changes in the width of the fabric.

It will be seen that after the first loop limb has been inserted and a corresponding limb 25 has been also inserted from the other side of the loom, the second limb of the first loop is still attached to the weft package 10 and gripped by a trapping device 15. This limb is then depressed into the path of one inserter and released from the trapping device, at the same time being cut from the supply by the severing device 14 associated with the trapping device 15. The second loop limb is similarly cut and released at the other side of the loom to complete a weaving cycle comprising the insertion of four picks.

Each disc performs a half-revolution during the formation of each loop, and the pairs of trapping and severing devices 14, 15 have changed positions in readiness for the formation of the next loop.

Figs. 5, 6 and 7 show clearly the formation of the weft loops by means of disc devices A, B at the two sides of the loom and the insertion of the loops to form picks a, b, c, d of the fabric α . These figures also show the positions of the weft inserting and withdrawing devices at the different stages of loop formation.

What we claim and desire to secure by Letters Patent is:—

1. A shuttleless loom comprising in combination means for measuring weft from a stationary supply at a side of the loom in the form of a loop whose length is sufficient for two picks, weft-inserting means adapted to engage each limb of the loop in turn and carry it part-way through the shed, and means for transferring the weft thus inserted to withdrawing means adapted to carry it through the remainder of the shed.

2. A shuttleless loom according to claim 1 comprising weft-inserting and withdrawing means in the form of rods provided with

means for effecting the transfer of weft from the inserting rod to the withdrawing rod.

3. A shuttleless loom according to claim 1 comprising weft measuring means at each side of the loom.

4. A shuttleless loom according to claim 1 comprising weft measuring means and combined weft inserting and withdrawing means at each side of the loom.

In testimony whereof we have hereunto subscribed our names.

HENRY DREYFUS.
